(57) **CLAIM**

The ornamental design for a keyboard and stand, as shown and described.

DESCRIPTION

FIG. 1 is a perspective view of the keyboard and stand, in a closed state, showing my design thereof;

FIG. 2 is a perspective view thereof in a partially open state; FIG. 3 is a perspective view thereof in a further partially open state;

FIG. 4 is a perspective view thereof in an open state;

FIG. 5 is a top view thereof in an open state without the stand; FIG. 6 is a front view thereof in an open state without the stand;

FIG. 7 is a side view thereof in an open state without the stand; and,

FIG. 8 is a bottom view thereof in an open state without the stand.

The keyboard stand is shown in broken lines in FIGS. 1-4 for environmental purposes only and forms no part of the claimed design. The portions of the keyboard shown in broken lines form no part of the claimed design.
